DESIGN FOR A STORAGE BATTERY CONTAINER

Joseph G. Monnin, San Leandro, Calif., assignor to U S L Battery Corporation of California,
Oakland, Calif., a corporation of California

Application March 11, 1936, Serial No. 61,583

Term of patent 7 years

To all whom it may concern:

Be it known that I, Joseph G. Monnin, a citizen of the United States, residing at San Leandro, in the county of Alameda and State of California, have invented a new, original, and ornamental Design for Storage Battery Container, of which the following is a specification.

Referring to the accompanying drawing, which constitutes a part of the specification:

The figure is a perspective view of a storage battery container showing my new design.

That end of the container not illustrated in said perspective view is substantially identical with the end illustrated. That side of the container not illustrated is substantially identical in design to the side shown, with the omission of the central medallion.

I claim:

The ornamental design for a storage battery container substantially as shown and described.

In witness whereof, I have hereunto subscribed my name.

JOSEPH G. MONNIN.
